UNITED STATES PATENT OFFICE.

JAMES P. SKARTCHSEARIS, OF JAMESTOWN, NEW YORK.

RAILWAY SWITCH AND SIGNAL MECHANISM.

Application filed May 13, 1921, Serial No. 469,281. Renewed August 14, 1922. Serial No. 581,839.

To all whom it may concern:

Be it known that I, JAMES P. SKARTCHSEARIS, a subject of the King of Greece, residing at Jamestown, in the county of Chautauqua and State of New York, have invented certain new and useful Improvements in Railway Switch and Signal Mechanism, of which the following is a specification.

This invention relates to a combined signal and switch operating mechanism and more particularly to that type adapted to be operated from the cab or front of a railway car such as defined and described in my Patent Number 1,371,937, patented March 15, 1921.

The primary object of the invention resides in the provision of a combined signal and switch operating mechanism wherein the switch point operating bar is preliminarily unlocked before the switch proper is actuated and simultaneously operating a signal or semaphore.

Another and very important object of the invention resides in the construction and provision of a combined signal and switch operating mechanism capable of being actuated either from a main line and a siding or branch line including provision for operating a second signal situated at a remote point from the juncture of the main and branch line whereby the direction of travel may be determined.

Another and very important object of the invention relates to a switch and combined signal and operating mechanism of the above class which will be simple in construction, highly efficient and positive in operation, consisting of comparatively few parts which may be easily installed and which is not likely to get out of order, and otherwise embracing and conforming to the essentials of safety requirements of devices of this type now being used.

With these objects in view and others which will be apparent as the description proceeds, the invention resides in the combination and arrangement of parts and in the details of construction hereinafter described and claimed, it being understood that within the scope of what is claimed, changes in the preferred embodiment of the invention can be made without departing from the spirit and scope thereof, and in which,

Figure 1 is a plan view of the signal and switch operating mechanism. 55

Fig. 2 is a detail view of one of the trip levers. 55

Fig. 3 is a front view of one of the trip levers showing the same in its relation to a rail. 60

Fig. 4 is a view taken on the line 4—4 of Fig. 1 showing the lock operating lever. 60

Fig. 5 is a view partly in section showing the switch point operating bar unlocked. 65

Fig. 6 is a similar view showing the bar in its locked position. 65

Fig. 7 is a fragmentary view of one end of the switch point operating bar. 65

Fig. 8 is a plan view of a modified form of a signal and switch operating mechanism. 70

Fig. 9 is a view partly in section showing another form of lock for the switch point operating bar. 70

Fig. 10 is a detail view of the end portion of the lock bar. 75

Referring to the drawings, wherein like parts designate corresponding parts throughout the specification, 5, 6, designate the main rails and 7, 8, the rails of the branch track having its switch point 9, 10 arranged for sliding movement with respect to the switch points 11, 12, of the main rails, all of which operate in a similar manner to my patent above referred to. It will be observed that the movable switch points 13, 14 of the main rails and the switch points 9, 10 operate simultaneously and in unison being connected to a transversely extending switch point operating bar 15, which I have shown positioned between the extended ties 16, 17 on which the switch operating mechanism is partly mounted. 80

The respective ends of the bar 15 extend transversely through a boxing or guide 18 and are slidably arranged therein for co-operation with a vertically movable lock bar 19 which is provided with a slot 20 for alignment with the transverse slot 21 in the boxing 18 to permit the switch operating bar 15 to slide therethrough. It will be also observed that the bar 15 is provided with an integral lug 22 near its ends which engages the lock bar 19 when in its raised position as clearly shown by Fig. 5. The lock bar 19 normally rests on the enlarged extension 25 of a bell crank lever 26 which I have shown 100

as pivoted at 27 to each end of the rail 16, the upper free end 28 of said bell crank lever passing through a slot 29 in the end of a second bell crank lever 30 positioned and 5 arranged at right angles thereto and pivoted as at 31 to the rail 16 above referred to.

The extreme outer ends of the switch operating bar 15 are provided with apertures 32 whereby the yokes 33 are connected to operate 10 the rods 34 and the bell crank lever 35 connected thereto so that the semaphores or signals 36, 37 may in turn be actuated by their respective connecting rods 38, 39 when the bar 15 and the switch points carried 15 thereby are actuated.

Each of the bell crank levers 30 are connected by a pair of cross operating rods 40, 41 connecting another bell crank lever 42, 43 which are shown as pivoted at 44 to 20 one of the ties. The last mentioned bell crank lever 43 is connected to the bent lever 44 by a connecting link 45, a pull rod 46 being in turn connected to said connecting link 45 and a trip 47 which I have shown 25 pivoted at 48 to an upwardly extending support 49 mounted on one of the ties 50 and positioned outside of the main rail 5, 6. The opposite end of the bell crank lever 43, above referred to, is connected by a rod 51 30 leading to and connected with a bell crank lever 52 disposed outside the rail 7 of the side track, another rod 53 being also provided for connection with the bell crank lever 52 and a trip 54 similar to the trip 35 47 and operating in the same manner to exert a pull on the rod 53 to actuate the mechanism to open and close the switch points. The connecting link 55, outside the main rail 6, which operates the bell crank 40 levers 42, 43, has connected at one end a signal operating rod 56 which operates a pivoted lever 57 connected by a rod 58 to a suitable signal or semaphore such as above described, whereby when the switch is operated to open or close the main line this 45 information will be apparent at the crossing somewhat removed from the side line.

In the actual operation of the switch, when it is desired to operate the switch points 9, 50 10 to permit travel on the side track, it will of course, be necessary to actuate the switch point operating bar 15 to the right assuming that the train is approaching in the direction of the arrow. When the trip 47 is 55 actuated, a pull will be exerted on the rod 46 and consequently to the link 45 whereby the bell crank lever 43 will actuate one of the cross rods 40 thus rotating the bell crank lever 30 and of course the bell crank lever 26 whereby the lock bar 19 is raised to the position shown by Fig. 5 to its open, 60 unlocked position, permitting the bar 15 to slide outwardly and to the right thus moving the switch points 9, 10 to engagement 65 with the switch points 11, 12 of the main

rails. It will of course be understood that the keyhole slots in the ends of the connecting links 45 and bent levers 44 permit the locking and unlocking of the lockbars just preliminary to the transverse movement of the switch point operating bar 15. The operation of the bar 15 in each instance, operates the semaphores 36, 37, as the case may be and also the signal and semaphore (not shown) positioned near the crossing 75 and somewhat removed from the switch. It will of course be understood that when the right hand lock bar is locked for instance, permitting travel on the main line, the left hand lock bar is unlocked and vice versa, so 80 that in unlocking the lock bar 19 to permit travel on the side line, the left hand trip 47 must be actuated and in the other position the right hand trip must be actuated. In other words, the operation of the switch is 85 somewhat of a criss-cross scheme, whereby a left hand trip operates the right hand locking bar and the right hand trip operates the left hand locking bar.

In the form of the invention shown by Fig. 8, the switch points 60, 61 of the main line, and the switch points 62, 63 of the branch line are also adapted to be operated by the switch point operating bar 64 which is held in its locked and unlocked position 95 by the mechanism subsequently to be referred to.

In this form of the invention, I have also resorted to the use of bell crank levers and connecting rods for operating the switch, it 100 being noted that the bell crank levers 65, 66 are pivotally connected as at 67 to one of the ties 68 and in turn connected to the switch point operating bar 64 above referred to. The bell crank levers 65, 66 are also 105 provided with keyhole slots 69, at their point of connection with the switch point operating bar, the opposite ends of the said bell crank levers being connected by a rod 70 to one end of a second T-shaped lever 71 110 pivotally mounted as at 72 on a rail 73 as clearly shown in said figure. A pull rod 72 also connects the respective T-shaped levers 71 with a trip 73 similar in construction to the trip 47 of the form of the invention above described, one of said T-shaped levers having a signal or semaphore operating rod 75 whereby a signal (not shown) may be operated in proximity to a crossing for instance whereby the position of the switch may be determined. Each lever has connected to its outer end a lock operating rod 76 extending into a casing or guide 77 secured to the cross tie 68 and an adjacent tie by flat plates 78 as clearly 115 shown by Fig. 9 of the drawing.

The respective lock rods 76 secured to the lever 77 are provided at their outer ends with sliding blocks 79 which are shown as cut away as at 80 to receive the ends 120 125 81 of the drawing.

of the switch point operating rod which extends within a slot formed in the casing or guide 77, the said lock being retained in its locked position and in abutting relation 5 with the ends of the bar 64 by a coiled spring 81.

In this form of the invention, the levers 71 are connected to a signal operating rod 83 which is adapted to be actuated by the 10 bell crank levers 84 connected thereto and pivotally mounted on one of the cross ties which are operated by a pull rod 86 connected to the trip 87 in the same manner as above described. In this form of the invention, the bell crank lever 88 and its pull rod 89 and trip 90 are positioned for operation by the car while travelling on the side track, the said bell crank lever 88 being of course 15 also connected to the signal operating rod 83 as clearly shown in said figure.

In this form of the invention, the operation which is similar to the operation described in connection with the form of the invention shown by Fig. 1, assuming that 20 the car is travelling from the left to the right as indicated by the arrow, when the trip 87 is actuated a pull will be exerted on the rod 86 resulting in the bell crank lever moving the rod 83 to the left, thus actuating 25 a signal (not shown) and also the respective T-shaped levers 71. As the T-shaped levers 71 are actuated in a clockwise direction, the lock rod 76 and block 79 connected thereto will be withdrawn unlocking the end of the 30 switch point operating rod or bar 64 permitting the same to move to the right, consequently moving the switch points 60, 61 in engagement with the rail of the main track, the operation of the levers 71 in turn 35 actuating the signal rod 75 whereby the position of the switch may be determined at a remote point such as the crossing referred to in connection with the operation disclosed by Fig. 1.

40 While I have shown my invention as designed for use in connection with railway rolling stock wherein considerable labor is dispensed with in operating the switch and signal, the mechanism is equally adapted for 45 electric railway toy train construction and track switch therefor with or without the locking mechanism, and such application of the invention is further contemplated as falling within the scope of the invention.

50 In the accompanying drawings, I have 55 illustrated my invention embodied in one form by way of example, and which in practice has been found to be highly satisfactory in obtaining the desired results. It 60 will be obvious however that other embodiments may be made and that various changes in the details of construction may be resorted to by those skilled in the art without departing from the spirit and scope of the invention. It is furthermore understood that the

invention is not necessarily limited or restricted to the precise elements shown except in so far as such limitations are specified in the subject matter being claimed.

Having shown and described my invention, what I now claim as new and desire to secure by Letters Patent of the United States is:—

1. In a combined railway switch and signal of the class described, in combination 75 with the switch points of a railway track, a signal and switch point operating bar 80 slideable with the said switch points, lever operated, vertically movable members outside the switch points for locking said bar, and a trip mechanism for releasing said locking means to actuate said bar and open or close the selective switch points.

2. In a combined railway switch and signal of the class described in combination 85 with the switch points of a railway track, a signal and switch point operating bar 90 slideable with the said switch points, lever operating locking vertically movable members outside the switch points cooperating 95 with the ends of said bar, and a trip mechanism for releasing either of said locking members preliminary to actuating said bar to open or close the selective switch points.

3. In a combined railway switch and signal of the class described in combination 95 with the switch points of a railway track, a signal and switch point operating bar 100 extending on opposite sides of a track slideable with the said switch points, vertically slideable locking members outside the switch points cooperating with the bar outside the track and trip mechanism for releasing either of said locking members preliminary to actuating the signal and said bar to open 105 or close the selective switch points.

4. In a combined railway switch and signal of the class described in combination 110 with the switch points of a railway track, a signal and switch point operating, transverse bar 115 extending on opposite sides of a railway track slideable with the said switch points, simultaneously operable lever actuated, vertically movable locking members positioned outside the switch points cooperating with the ends of said bar to lock and unlock the same as the switch points are actuated, and trip mechanism for actuating said locking members preliminary to operating the signal and said bar to open and 120 close the selective switch points.

5. In a combined railway switch and signal of the class described in combination 125 with the switch points of a railway track, a signal and switch point operating bar transversely slid 130 with the switch points, bent levers connected to said bar, a bell crank lever and link connected to each of said bent levers, a pull rod and operating trip therefor on each side of the track to

actuate said bent levers and switch point operating bar, lever operated, vertically movable locking members cooperating with said bar at its respective ends and outside 5 of the switch points and means for shifting said bar and the selective switch points at the instant one of said locking members is unlocked.

6. In a combined railway switch and signal of the class described in combination with the switch points of a railway track, a signal and switch point operating bar transversely slidable in two directions with the switch points, bent levers connected to 10 said bar, a bell crank lever and link connected to each of said bent levers, a second set of bell crank levers positioned on opposite sides of the track in proximity to the ends of the switch point operating bar and 15 diagonal operating rods connected to the opposite, first mentioned bell crank levers, locking members cooperating with the ends of said switch point operating bar operatively connected with the second set of bell 20 crank levers, and pull rods and trips therefor directly connected to each of said links whereby said bar and the selective switch 25 points may be shifted at the instant one of said locking members is unlocked.
- 30 7. In a combined railway switch and signal of the class described in combination with the switch points of a railway track, a signal and switch point operating bar transversely slidable with said switch points,

lever operated, vertically movable locking 35 members cooperating with the ends of said bar and trip mechanism positioned outside of the track for releasing either of said locking members and actuate said bar to open and close the selective switch points. 40

8. In a combined railway switch and signal of the class described in combination with the switch points of a railway track, a signal and switch point operating bar transversely slidable with said switch points, 45 lugs carried by said bar near the ends thereof, boxings having transverse apertures therein rigidly secured outside of the track for receiving the ends of the bar, locking members slidable within the boxings and co-operating with the lugs and trip mechanism positioned outside of the track for releasing either of said locking members preliminary to the shifting of said bar and the 50 selective switch points.

9. In a combined railway switch and signal of the class described, in combination with the switch points of a railway track, a signal and switch point operating bar slid- 55 able with the said switch points, vertically movable members, outside the switch points for locking said bar, and a trip mechanism for releasing said locking members to actuate said bar and open or close the selective switch points.

In testimony whereof, I affix my signature hereto.

JAMES P. SKARTCHSEARIS.
